UNITED STATES PATENT OFFICE.

OWEN G. ARNOT, OF BAKERSFIELD, CALIFORNIA.

ROTARY TOOL.

Application filed October 21, 1922. Serial No. 595,944.

To all whom it may concern:

Be it known that I, OWEN G. ARNOT, a citizen of the United States, residing at Bakersfield, in the county of Kern and State of California, have invented new and useful Improvements in Rotary Tools, of which the following is a specification.

This invention relates to drill bits and more particularly to drill bits for deep well rotary tool rigs.

It is an object of the invention to provide a multiple bladed tool. Another object is to provide a multiple bladed tool having a single split shank.

Another object is to provide a rotary bit having great length of life so as to be operable for a much longer period before removal from the well hole for sharpening. Another object is to provide a fish tail bit with more than two cutting points and all of which are substantially symmetrically arranged with respect to the center of rotation of the bit and to provide a bit which will not readily clog or choke up in the well hole. It is also an object to provide a multiple bladed bit with more than two cutting points so as to secure an effective cutting action to run the hole true and straight and to overcome the tendency, as found in a single blade fish tail bit, to shift from a true line of cut.

Another object is to provide a fish tail bit with the peculiar arrangement of water courses, one of each being on the outside faces of the bit and one centrally of the bit.

Other objects and advantages will be made manifest in the following specification of an embodiment of the invention illustrated in the accompanying drawings, wherein—

Figure 1 is a side elevation of the improved bit looking toward edges of its multiple blades.

Fig. 2 is a bottom end plan of the bit.

Fig. 3 is a side elevation of the inside face of one of the bits.

The improved fish tail bit of my invention consists of a sectional construction in which a plurality of blade-like sections 2 are utilized, each of these blades having at its upper end a shank or head portion 3. Each shank portion 3 is provided with a meeting or abutment face 4 so that the sectional parts of the bit may be assembled with the respective shank portions 3 in abutment at their faces 4. In the present case, each shank

section 3 is substantially semi-circular and its abutment face is diametrical, and two of the sections are adapted to be placed face to face and to thus position the blades 2—2 in transverse opposition. The sections of the bit may be rigidly secured together to act as a unitary cutter, and means are here shown comprising exterior threads 5 on the tapered shank portions 3, which threads are adapted to be engaged by a complementary drill 63 socket or sleeve, not shown, and whereby the bit is rotated.

For fastening the pieces together until secured in a drill collar or sleeve, they may be joined by transverse bolts or rivets 6. The upper ends of the shanks 3 are shown as turned down to form stem sections 7, and these sections when set face to face form a cylindrical projection which is externally screw-threaded at 8 to receive a fastening 75 collar 9 which is shown of less diameter than the upper end of the threaded shank portion.

The lower ends of the blades 2, which may be tapered downwardly, are shown as provided with usual fish tail cutting points 2a. The cutting points, as clearly shown in Fig. 2, are all arranged in symmetrical order on diametrically opposite sides of the axis of the bit, and by this arrangement of four cutting points, the cutting action of the bit will be maintained more nearly to a straight line path during the rotation of the bit than is possible where fish tail bits of only two cutting points are driven.

Another feature of the invention is the provision of water courses through the shank of the bit. Such courses are here represented as longitudinal apertures 10, 11 and 12. The aperture 10 is produced by forming grooves 95 axially in the meeting faces 4 of the shank section 3, so that when these sections are placed face to face the groove will form an axial water course 10 which will discharge downwardly between the spaced blades 2—2 of the bit. The water courses 11 and 12 may be formed as drill holes run from the upper end of the shank sections 3—3 to the lower ends of the shanks where the water courses discharge outside of the outer faces of the 105 blades 2—2.

Further embodiments, modifications and changes may be resorted to within the spirit of the invention as here claimed.

What is claimed is:

1. A rotary bit comprising a plurality of blades each having oppositely twisted cutting ends, the blades having portions forming a shank body to receive a driving means, and water courses extending through the assembled shank body and discharging outside of the blades and between the blades.
2. A rotary drilling tool comprising blades having opposite, parallel portions and each blade being provided with a fish-tail cutting end, the corners of the fish-tail ends all being twisted forward in the direction of the rotation of the tool.
3. A rotary bit comprising two blades,

each blade carrying a portion forming half a shank body, the two half shank bodies being secured together and externally screw-threaded to form a pin for connection to a drill stem, the lower ends of the blades being of fish tail form, the cutting corners being twisted in the direction of rotation. 15

4. A rotary bit comprising two blades, the lower ends of each blade being of fish tail form, and the cutting corners being twisted in the direction of rotation. 20

In testimony whereof I have signed my name to this specification: 25

OWEN G. ARNOT.
